LUGGAGE HANDLE

Bela G. Szabo, Pittsburgh, Pa., assignor to Bruce Plastics, Inc., Pittsburgh, Pa.

Filed May 7, 1971, Ser. No. 141,451

Term of patent 14 years

Int. Cl. D8—06

U.S. Cl. D8—154

FIG. 1 is a plan view of a luggage handle showing my new design;

FIG. 2 is a front elevational view;

FIG. 3 is a vertical sectional view along line 3—3 of FIG. 2;

FIG. 4 is a sectional view along line 4—4 of FIG. 2;

FIG. 5 is a horizontal sectional view along line 5—5 of FIG. 2;

FIG. 6 is a horizontal sectional view along line 6—6 of FIG. 2; and

FIG. 7 is a horizontal sectional view along line 7—7 of FIG. 2.

I claim:

The ornamental design for a luggage handle, as shown.
